UNITED STATES PATENT OFFICE.

WILLIAM K. GIBBONEY, OF BUFFALO, NEW YORK, ASSIGNOR TO THE
PITTSBURGH REDUCTION COMPANY, OF NEW KENSINGTON, PENN-
SYLVANIA, A CORPORATION OF PENNSYLVANIA.

CURRENT-REGULATOR.

No. 821,936.

Specification of Letters Patent.

Patented May 29, 1906.

Application filed November 19, 1904. Serial No. 283,391.

To all whom it may concern:

Be it known that I, WILLIAM K. GIBBONEY, of Buffalo, Erie county, New York, have invented a new and useful Improvement in Current-Regulators, of which the following is a full, clear, and exact description, reference being had to the accompanying drawing, forming part of this specification, which shows in diagram view apparatus embodying my invention.

My invention has been especially designed for the regulation of a group of electrodes in an electric furnace by which they can be regulated independently and automatically, so as to maintain constant and uniform conditions, and by which, if desired, the current applied to all the several electrodes may be varied and adjusted simultaneously. Where a number of electrodes are used in a single electric furnace regulation of this kind is of great importance.

I provide each electrode with a regulating electromagnetic device which is operated automatically by a current derived from the current passing through the electrode, and I oppose the action of such derived current by an independent electromagnetic force. By varying the strength of the said opposing electromagnetic force by appropriate means the current supplied to the electrode may be varied as desired.

In the accompanying drawing I show two electrodes 22, which are regulated by the apparatus which I am about to describe; but the invention can be applied to the regulation of any number of electrodes, all that is essential being to provide each of them or each unitary group of them with individual regulating devices constructed in accordance with my invention.

The electrodes 22 are supplied with current from a circuit 3 and a generator 4, which may be an alternating-current generator, as shown on the drawing, or it may be a generator of direct current. Each electrode is provided with a mechanical feeding device by means of which it is either raised or lowered in accordance with the current conditions necessary to be maintained.

I do not show the feeding mechanism in the drawing; but it may be of any suitable type, and it is controlled by my improved regulating device. This device in the form

in which I show it comprises an oscillatory armature 4', mounted between pole-pieces 5, the field being constituted by coils 6 6, wound upon the pole-pieces. The strength of the field is regulated by a rheostat 7, and preferably also by a rheostat 8, which is in the circuit with the armature-coil, the field and armature coils being in the circuit which is independent of the circuit to be controlled and is preferably constant, or nearly so, so that a torque of constant force capable of manual regulation by means of rheostats 7 and 8 is applied to the armature 4'. The independent armature-circuit is not indispensable, since the device may be operated with the armature-coils short-circuited, or these coils may be removed altogether. The armature-shaft carries a lever 9, at each end of which are contacts 10 and 11, respectively adapted to dip into mercury-cups 12 13. These cups are in circuits 14 15, supplied from a suitable source 16 and controlling, respectively, the magnets 17 and 18, one of which controls the actuating mechanism for raising the electrode and the other of which controls the mechanism by which the electrode is lowered, so that if one of the contacts is made at the mercury-cups the electrode will be lowered, and if the contact is made at the other cup the electrode will be depressed in the furnace, thereby increasing or diminishing the resistance of the electrode-circuit and correspondingly diminishing or increasing the current flowing.

19 is a magnet which I show in the drawing as a solenoid-magnet. Where an alternating current is used, it is preferably arranged, as shown in the drawing, in a circuit with a series converter 20, by which a current of less voltage, but varying directly with the current in the main circuit, is supplied to magnet 19. This magnet has an armature 21, attached to the lever 9, which tends to draw the lever down, and thus move it in opposition to the constant force applied to it by armature 4'. The motion of the lever is restricted by the post 22, having suitable stops 22'. However, if a direct current is used the derived regulating-current will be obtained by means of a shunt from the main current.

The operation of the device as thus constructed is as follows: The armature 4' and its actuating-circuit are initially adjusted,

so that the torque of the armature will be just sufficient to counterbalance the pull of the solenoid-magnet 19 when the electrode is in proper position in the furnace and a normal current is passing through it. This will keep the lever 9 in a horizontal position and will hold both of the contacts 10 and 11 out of the mercury-cups, and therefore neither of the electromagnets 17 or 18 will be actuated and the electrode will remain stationary in the furnace. If, however, the electrode should be too high in the furnace, the resistance of its circuit being increased thereby less force will be exerted through magnet 19 on the armature 21, so that the torque of the armature 4' will overbalance the action of the magnet 19 and will move the lever so as to make contact in the mercury-cup 12. The current will thereupon flow through the magnet 18, which will cause the feeding device to move the electrode down in the furnace, thus lowering the resistance of the electrode-circuit and increasing the current which passes through it. When the current has reached a point high enough to exert upon the armature 21 a force sufficient to counterbalance the torque of the armature 4', it will move the lever 9 and will open a circuit at the mercury-cup 12, thus deenergizing the magnet 18 and causing the feed of the electrode to stop. If the current passing through the electrode should increase, an increased pull will be exerted by the magnet 19, which will move the lever 9 sufficiently to make contact at the mercury cup 13. This will energize the magnet 17, which in turn will control the feeding mechanism of the electrode, so as to raise it in the furnace until it has reached a point where the current is restored to its normal condition. The force exerted by the magnet 19 will then balance the torque of armature 4, again opening circuit at 13, so that the electrode will come to rest. In this way the apparatus will respond quickly to very slight changes in the position of the electrode and the current passing therethrough, each electrode being individually regulated by its own mechanism and all the electrodes of the furnace being kept in such positions as to maintain constant conditions of resistance and of current in their respective circuits.

I may regulate the current which is supplied to any electrode not only by operation of rheostats 7 and 8, but by a switch 23, by which one of the field-coils 6 may be cut out of the circuit and the current passing through the corresponding electrode thus decreased to about one-half the quantity at which the device was originally adjusted. This is often important—as, for example, when by reason of defective composition some of the electrodes may become unduly heated. In such case the current in these electrodes can be lowered without affecting the current passing through the other and normally acting elec-

trodes. The current may thus be regulated manually in any one or in all of the electrodes by cutting out of circuit one of the field-coils of one or all of the regulating devices.

It will be understood by those skilled in the art that the mechanism described above may be varied in many ways, although I deem the form which I illustrate to be preferable. Thus instead of the solenoid-magnet 19 and the motor 4 other forms of electromagnetic devices may be substituted, the essential being only that the magnetic regulator by which the current is controlled is opposed by an electromagnetic device. This has great advantages over the use of a spring or a weight for the opposing force, because it can be adjusted with great accuracy and is not subject to the disturbing influences which impair the value of adjustable springs or weights. I also find that a weight 24, traveling on a screw 25, attached to the lever 9, assists materially in giving a better regulation, as such adjustable counterpoise can be shifted toward or from the axis of rotation, and the opposing electromagnetic force can be slightly varied, as desired. I show this construction in the drawing.

The apparatus may be modified in many ways, since

What I claim is—

1. Means for regulating furnace-electrodes, consisting of motive devices arranged to move the electrode in opposite directions, normally open circuits for the motive devices, an electromagnetic regulating device operated by current derived from the electrode-circuit and proportional thereto, said device being arranged to control the circuits of the motive devices, and a magnetic device arranged to oppose the action of the regulating device and energized from a separate source; substantially as described.

2. Means for regulating furnace-electrodes, comprising motive devices for feeding the electrode, normally open circuits for the motive devices, an electromagnetic regulating device operated by current derived from the main current and proportional thereto, said regulating device controlling the circuit of the motive devices, a magnetic device arranged to oppose the action of the said regulating device energized from a separate source, and means for varying the force of the opposing magnetic device; substantially as described.

3. The combination with a group of electrodes, each of which is provided with motive devices for raising and lowering it, of electromagnetic regulating devices operated by current derived from the main current and proportional thereto, each of the regulating devices being arranged to control the circuits of the motive devices of one of the electrodes, magnetic devices energized from a separate source, and arranged to oppose the action of

the first-named regulating devices and means for adjusting the force of the opposing magnetic devices; substantially as described.

4. In means for regulating furnace-electrodes, the combination with separate motive devices for raising and lowering the electrode, of a regulator comprising an armature and field, in circuit with a source of current independent of the current to be regulated, 10 an electromagnetic device operated by a current derived from the main current and proportional thereto and arranged to act in opposition to the armature, and circuit-closing means for the motive devices controlled by 15 the conjoint operation of the armature and of the opposing device; substantially as described.

5. Means for regulating furnace-electrodes, consisting of separate motive devices for raising and lowering the electrode, normally open circuits therefor, an armature and field in circuit with a source of current independent of the current to be regulated, an electromagnetic device operated by a current derived 25 from the main current and proportional thereto, and circuit-controlling means for the cir-

cuits of the motive devices operated by the opposing actions of said armature and electromagnetic device, together with means for regulating the torque of the armature; sub- 30 substantially as described.

6. A current-regulator, comprising an armature and field in circuit with a source of current independent of the current to be regulated, normally open circuits including motive devices, a lever carried by the armature-shaft, and carrying contact devices for controlling said circuits, and an electromagnetic device operated by a current derived from the main current and proportional thereto 40 and acting upon said lever in opposition to the armature, together with means for adjusting the force of the opposing actions of said armature and electromagnetic device; substantially as described.

In testimony whereof I have hereunto set my hand.

WILLIAM K. GIBBONEY.
